TUNNEL LINING AND METHOD OF FORMING
THE SAME

Kenneth C. Bellows, Sheridan, Wyo.

Application September 12, 1945, Serial No. 615,746

1 Claim. (Cl. 61—45)

1

This invention relates to improvements in and methods of forming tunnel linings, and more particularly to linings for aqueducts and the like.

It is conventional practice in constructing tunnels to provide a concrete lining around the entire periphery thereof. Such lining provides reinforcement for the roof of the tunnel, preventing cave-ins and, in the case of aqueducts, such linings have the additional functions of preventing contamination and loss of the water by seepage and promote easy flow of the water through the tunnel. Such linings have heretofore been formed in the following manner. The base or invert which may extend up to about 45° on either side is poured and after the concrete has set, rails are laid, or they may be embedded in the concrete during pouring, to facilitate delivery of materials for the balance of the lining. Forms extending around the balance of the periphery of the tunnel are then placed in position with their bottom edges resting on the upper edge of the base or invert. These forms are about 20 to 25 feet in length. Since the rock and strata through which the tunnels are bored tend to break down unevenly, there may be quite high gaps around and above these forms so that it is necessary to deliver the grout behind the forms under considerable pressure to force it upwardly to fill such gaps. This in turn necessitates the placing of bulkheads at each end of the forms so as to contain the grout therein. Due to the unevenness of the walls, these bulkheads must be painstakingly pattern-cut to fit the wall surfaces and then caulked. In addition, considerable shoring is required to hold such forms in the desired position. Making these bulkheads and shoring the forms requires a great deal of highly skilled hand labor and adds considerably to the cost of the tunnel lining. In addition to the expense, such operation is undesirable due to the discontinuity of the operation of placing a form, filling grout between the form and the tunnel wall, and then ceasing the pouring until another form has been set in position and readied for pouring. Since the mixers and pumps are thus idle for considerable periods, they must be cleaned after each form is filled to prevent any grout becoming set therein while the next form is being placed in position.

It is accordingly an object of the present invention to overcome the foregoing disadvantages and to provide a method of forming tunnel linings which is considerably cheaper than present methods.

It is another object to provide a method of

2

forming tunnel linings which permits pouring the concrete grout continuously.

It is still another object to provide a tunnel lining that has a smooth surface so as not to impede the flow of fluids therethrough.

It is a further object to provide a tunnel lining which is simple in design and rugged and durable in use.

It is a still further object to provide a highly impervious concrete tunnel lining.

The foregoing and further objects will be apparent from the specification and drawing, wherein:

Figure 1 is a fragmentary longitudinal section of a tunnel showing my improved mode of forming the lining;

Figure 2 is a vertical section along line II—II of Figure 1;

Figure 3 is a cross section of a suitable form for casting the arch or shell members;

Figure 4 is a cross section of an arch or shell member of my invention;

Figure 5 is an enlarged detail of the joint between the arch or shell members and the invert or base; and

Figure 6 is an enlarged detail of the joint between the ends of arch or shell members.

Referring more particularly to the drawing, the numeral 2 designates the bore of the tunnel in which a concrete base or invert 4 has been continuously poured. Disposed on the invert 4 are shell liners or arches 6 formed of Portland cement or other suitable plastic, which have a tongue and groove connection 8 at their upper edges. The ends of the shell members 6 are beveled as at 10 as shown more clearly in Figure 6. The bevel 10 is designed to compensate for any irregularities between the shells and to provide an annular groove 12 which may be filled with mortar or suitable calking material 14 as a finishing step in the formation of the tunnel lining. The lower edge of the shells 6 and the outer edges 4a of the invert 4 are shown in detail in Figure 5.

A smooth bearing portion 16 is provided at the outer portion of the invert with an upstanding shoulder 18 which may have a beveled upper edge 20. The shells are cast with a smooth lower surface 22 to rest on the bearing surface 16, and an adjoining shoulder 24 which is beveled as at 26, complementary to the bevel 20. A sealing pad 28 of impregnated asbestos or the like may be disposed between the shoulder portions 18 and 24 of the invert and shells, respectively.

This provides an inwardly opening groove 30 which, like the end joint, may be filled with mor-

tar or suitable calking material 32 as a finishing step in the formation of the tunnel lining.

A continuous concrete backfill 34 is provided behind the shells or arches by delivering concrete grout through a pipe 36 connected to a suitable pump or placing equipment 38. The placing equipment may be of any conventional type such as a pair of reciprocating piston force pumps or compressed air may be used to deliver the grout. The length of the pipe 36 is such that it permits a plurality of shells to be placed in position between the point of discharge and the placing equipment. As shown in Figure 1, five pairs of shells are provided ahead of the point of discharge 40 of the grout. The number of shells required of course depends on their length and the height of the tunnel. In general, it may be stated that the length of the pipe 36 is at least long enough to permit four feet in length of the liner to be positioned for each foot in height of the tunnel, plus room for an additional pair of shells to be erected as the placing equipment 38 retreats. This permits the lining operation to be carried on continuously since, as the backfill 34 behind one pair of shells is being made, an additional shell is being erected adjacent the placing equipment.

As shown in Figure 1, the end of the pipe 36 or point of discharge 40 is maintained a considerable distance behind the downward flow of grout so as to provide sufficient pressure to force the grout upwardly into gaps, such as illustrated at 44.

The shells may be cast on a form 50 such as is shown in Figure 3. It is understood that the shells are cast on right and left hand forms so that proper tongue and groove, and inwardly opening grooves, are obtained. The shells are preferably formed of a rich, rather dry mix of cement to obtain sufficient strength with a thin cross section and should be vibrated during casting to insure solid walls and a smooth inner surface 55. Such smooth inner surface tends to promote the easy flow of fluids through a tunnel lined in accordance with the teachings of my invention. Despite the use of a rich mix for the shells, the total amount of Portland cement used is not increased thereby, since a leaner mixture of cement may be used in the backfill 34 and sufficient strength obtained by reason of the backfill being poured continuously. Moreover, the continuous pouring of the backfill forms a continuous monolithic backfill which has no joints and is therefore quite impervious. Calking of the shell liners, as described hereinbefore, also increases the imperviousness of the lining.

In forming tunnel lining, as herein described, the bore 2 of the tunnel should, in most instances, be completed before lining operations are started. The invert 4 is then poured and, if the height of the tunnel is sufficiently high to make it desirable, side walls may be formed. Lining operations are then begun by placing the desired number of the arch forming shells or liners in position as before described. The outer end of the outer pair of shells may then be calked or bulk-headed or this may result from a facing being formed at the entrance to the tunnel. Grout is then forced behind the arch forming shells in a continuous pouring operation. As the placing

equipment 38 is withdrawn, additional pairs of arch forming shells are erected so that the desired number of shells to keep the total length thereof in front of the point of discharge is greater than a total of four feet in length for each foot of height of the tunnel. Thus the erection of the arches never interferes with the pouring of the monolithic backfill. In average tunnel operations, the lining will proceed from one end towards the other end and the arches and other material will be brought in through the end of the tunnel which has been lined. In this way, the delivery of the arches cannot interfere with the movement or operation of the placing equipment. However, in the case of large diameter tunnels, it might be desirable to start the lining operations in the midportion of the tunnel and work away from such point towards both portals simultaneously.

While I have shown and described one specific embodiment of my invention, it will be understood that this embodiment is merely for the purpose of illustration and description and that various other forms may be devised within the scope of my invention, as defined in the appended claim.

I claim:

A method of forming a lining in a tunnel bore comprising forming a base, placing a plurality of longitudinally aligned sectional arches on said base, the length of said erected arches being at least four times the height of the tunnel bore, forcing concrete grout behind said arches to form a backfill, maintaining the point of discharge sufficiently back of the poured material to obtain sufficient back pressure to force the concrete grout upwardly to completely fill the space between the arches and the top of the bore, erecting additional arches as the concrete grout is forced behind the previously erected arch sections to keep the length of the erected arches in front of the point of discharge a distance of at least four times the height of the bore and continuing forcing the concrete grout behind the newly erected arch sections whereby the erection of the arches and the forcing of the concrete grout backfill therebehind continues substantially uninterruptedly to thereby obtain a substantially continuously poured monolithic backfill.
